UNITED STATES PATENT OFFICE.

JAMES L. MARRIOTT, OF OSKALOOSA, IOWA.

REEL.

1,297,380.

Specification of Letters Patent. Patented Mar. 18, 1919.

Application filed December 7, 1918. Serial No. 265,763.

To all whom it may concern:

Be it known that I, JAMES L. MARRIOTT, a citizen of the United States, residing at Oskaloosa, in the county of Mahaska and 5 State of Iowa, have invented certain new and useful Improvements in Reels, of which the following is a specification, reference being had to the accompanying drawings.

This invention relates to certain improvements in reels, and has relation more particularly to a device of this general character especially designed and adapted for use in connection with hose, and it is an object of the invention to provide a device 10 of this general character with novel and improved means whereby the reel is conveniently and effectively mounted in applied position, and whereby a hose or the like wound upon the reel is protected against the 15 elements.

The invention consists in the details of construction and in the combination and arrangement of the several parts of my improved reel whereby certain important advantages are attained and the device rendered simpler, less expensive, and otherwise 20 more convenient and advantageous for use, as will be hereinafter more fully set forth.

The novel features of my invention will 25 hereinafter be definitely claimed.

In order that my invention may be the better understood, I will now proceed to describe the same with reference to the accompanying drawings, wherein:

30 Figure 1 is a vertical, sectional view taken through a reel constructed in accordance with an embodiment of my invention; and

Fig. 2 is a horizontal sectional view taken 35 through my improved reel as herein described.

As disclosed in the accompanying drawings, my improved device comprises two side frames A each substantially in the form of an equi-lateral triangle with the apex 40 thereof forwardly directed.

The frames A are spaced apart in horizontal alinement and the base members 1 of the frames are tied or connected by the rigid straps or members 2 arranged in pre- 45 determined vertical spaced relation. Dis- posed through the straps or members 2 sub- stantially midway thereof is a removable bolt or pin 3 which also coacts with the bracket 4 whereby the frames A may be 50 supported for swinging movement in a hori- 55

zontal plane and as the occasions of practice may require.

The lower inclined member 5 of each of the frames A is continued by an upwardly and forwardly directed extension or bar 6 bolted 60 or otherwise secured to the member 4 and the upper end of the extension or arm 5 terminates in substantially horizontal plane as the upper end of the frame A.

H denotes a hood substantially in the form 65 of an inverted V and which is suitably affixed to the upper end portions of the frames A and the extensions or arms 5, whereby the reel R and the hose or the like wound upon the reel are protected against the elements. 70

The reel R comprises a central shaft or axle 7 rotatably disposed through the apices of the frames A and through the lower end portions of the extensions or arms 4. Detachably engaged with an end portion of the 75 shaft or axle 7 is a crank 8 or the like whereby the requisite rotation may be imparted to the reel R. When not in use the crank 8 may be removed and suspended from the hood H or the like.

Radiating from the opposite end portions of the shaft or axle 7 are the arms 9 preferably produced from elongated flat strips of metal, and the outer end portion of each of said arms 9 is initially slotted longitudinally 80 so that a side marginal portion of the arm may be bent inwardly to afford a finger or lug 10 substantially at right angles to the arm.

Bolted or otherwise secured to each pair 90 of longitudinally alined fingers or lugs 10 is a metallic slat or strip 11 about which the hose or the like is adapted to be wound, and it will be self-evident that the second or unbended marginal portion of each of the 95 arms 9 afford guards 12 to hold the hose wound upon the reel against displacement.

By having my improved device supported for swinging movement, preferably in a horizontal plane, it will be obvious that the 100 device may be readily swung into a position to facilitate the winding of the hose or the like upon the reel R without the necessity of any particular adjustment or laying out of the hose or the like.

From the foregoing description, it is thought to be obvious that a reel constructed in accordance with my invention is particularly well adapted for use by reason of the convenience and facility with which it 110

may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

What is claimed is:

1. A device of the character described, comprising in combination, side frames triangular in form with their apices forwardly directed, members connecting the base portions of said frames and affording securing means, a reel supported by the apex portions of the frames, and upwardly and forwardly inclined arms secured to the apex portion of the frames and terminating in a plane substantially flush with the top of the frames, and a hood secured to the upper end portions of the frames and arms.
2. A device of the character described, comprising in combination, side frames triangular in form with their apices forwardly

directed, members connecting the base portions of said frames and affording securing means, a reel supported by the apex portions of the frames, and upwardly and forwardly inclined arms secured to the apex portion of the frames and terminating in a plane substantially flush with the top of the frames, and a hood secured to the upper end portions of the frames and arms, said hood being substantially in the form of an inverted V.

3. A device of the character described comprising, in combination, side frames, spaced members connecting the side frames, a pin disposed through said members at substantially their longitudinal centers, a bracket engaged with the opposite end portions of the pins whereby the connected frames have swinging movement about the pin, and a reel supported by the frames.

In testimony whereof I hereunto affix my signature in the presence of two witnesses.

JAMES L. MARRIOTT.

Witnesses:

F. E. COLVILLE,
A. F. DE WITT.
